UNITED STATES PATENT OFFICE.

MICHAEL W. McCARDLE, OF CHICAGO, ILLINOIS.

CONTAINER FOR ELECTRIC IRONS.

Application filed February 25, 1924. Serial No. 694,846.

To all whom it may concern:

Be it known that I, MICHAEL W. McCARDLE, a citizen of the United States, residing in Chicago, in the county of Cook and 5 the State of Illinois, have invented certain new and useful Improvements in Containers for Electric Irons, of which the following is a specification, reference being had to the accompanying drawings, forming a part 10 thereof.

The purpose of this invention is to provide a container for an electric iron in which the same may be safely stored when the iron is still hot upon the conclusion of a period 15 of use, and also in which the iron may be conveniently and effectively exposed for sale and transported, and which may also accommodate the electric cable of the iron without liability to injury thereof by reason of exposure to the heat of the iron, particularly 20 as by contact therewith. It consists in the elements and features of construction shown and described, as indicated in the claims.

In the drawings:

25 Figure 1 is a perspective view of a container embodying this invention shown closed.

Figure 2 is a perspective view of the container open, showing the iron therein as 30 when exposed for sale in the container.

Figure 3 is a fore-and-aft vertical section of the case closed, of the form shown in Figure 2.

Figure 4 is a view similar to Figure 2, 35 showing a different form of cable-carrying means.

Figure 5 is a section at the line 5—5 on Fig. 4.

Figure 6 is a section at the line 6—6 on 40 Fig. 5.

Figure 7 is a view similar to Figure 2 showing another modification.

Figure 8 is a fore-and-aft vertical section of the form shown in Figure 7.

45 Figure 9 is a top plan view of the form shown in Figure 7 without the top, showing the cable in place as stored in the case.

Figure 10 is a view similar to Figure 2 showing another modification.

50 The construction shown in the drawings comprises a case which is designed to be made of sheet metal, rectangular in form, having a top, A, hinged at the rear edge for opening up rearwardly and a front wall, B, hinged at the lower edge for opening down forwardly, and having space for storing an

electric iron indicated at C, lodged upon a suitable stand, H, employed for like purposes when the iron is in use, said stand having its three legs, h, h, h, engaged in depressions, h¹, struck from the bottom, H¹, of the case, and serving as short legs by which the case rests upon the table or shelf where it may be placed or stored, and which insure a limited air space below the case for 60 ventilation, and to prevent heating through from the iron to the shelf or table. The specific purpose to which this invention is directed with respect to the details of construction of the container shown is to provide means for storing the electric cable of the iron in the container with the iron, and safe from danger of being injured from the heat of the iron when it is so stored with the iron still hot from recent use. For the 65 purpose of thus storing the cable two provisions are made in the structure shown in Figures 1, 2 and 3 of the drawings, either or both of which may be used, both being in service when, as is frequently desirable, two 70 cables are provided for the iron having different terminals adapted for engagement with different forms of sockets. For this purpose there is mounted upon the under side of the hinged cover extending 75 along the side next to the hinge, a pocket formed by a sheet metal stamping, D, which is suitably flanged and riveted to the cover and shaped so as to be accommodated in the space above the body of the iron behind the 80 handle thereof when the cover is in closed position with the iron in the case. For admitting the cable in this form the pocket is made open at the ends as seen in Figure 85 2 for inserting and removing the cable. In addition to the pocket, D, mounted upon the cover as above described, there is desirably provided a second pocket, E, which is mounted upon the inner side of the front wall extending along the upper edge thereof 90 opposite the hinged edge, for protruding into the case when said front is at closed position, above the body of the iron and forward of the handle, that is, in the position at the opposite side of the handle from the pocket carried by the cover at closed 95 position. This pocket, E, is formed similarly to the pocket, D, open at the ends as seen in Figure 2 for inserting and removing the cable.

Or instead of the pockets, D and E, open at the ends, there may be, as shown in Fig-

ure 10 at D^x and E^x , respectively, pockets having the side which is forward at open positions of the top and front, respectively, open along the full length of that side as seen at d^x and e^x , respectively, these open sides being at closed position closed by the back wall and top respectively of the case.

Instead of a pocket or pockets as described and shown in Figure 10 for holding 10 the cable, there may be mounted in similar positions on the cover and front wall respectively, capped, flanged or cross-headed posts around which the cable may be coiled. Such construction is shown in Figure 4 in 15 which flanged studs or posts, F, F, are shown mounted in the cover near the opposite ends, spaced far enough therefrom for coiling the cable around the posts, and in which cross-headed or T-shaped posts, G, G, are shown 20 mounted in the hinged front, B, for projecting inward into the case when said front is at closed position, the cross heads being preferably transverse rather than longitudinal with respect to the container, and 25 thereby being vertical at the closed position of the front wall by which the coiling of the cable is somewhat facilitated, as compared with longitudinally extending cross heads.

In the form shown in Figures 4 and 5, the 30 posts, F, on the hinged top desirably have their flange heads as shown formed in one piece, constituting a deflector, K, for deflecting the hot air rising from the iron away from the cable coiled on the posts, F; and 35 ventilating apertures are designedly made in the top, A, as seen at $a-a$ in position for causing the air current to be normally biased toward the same deflected course. Also, in 40 this form, a deflecting shield, G¹, is desirably provided below the posts, G, in position for deflecting the hot air rising from the iron away from the cable coiled on the posts. In the form shown in Figures 2, 3 and 10, 45 in which the cable mounting holding means are in the form of pockets, it is desirable that these pockets should be ventilated by the apertures situated so as to cause circulation of air from the outside through the 50 pockets, tending to prevent the circulation of hot air from the iron through its pockets. With this in view, the pocket, D, it will be noticed, has the wall, which, at closed position, seats against the back wall of the case, 55 consisting only of a rudimentary strip, E¹, extending along the side next to the hinge and the back wall of the case has apertures, $m-m$, registering with the open area of the wall below this rudimentary strip; and the 60 top, A, has a row of apertures, a^1 , which open from the upper side of the pocket when the top, A, is in closed position so that there is obtained a circulation of air from the outside through the pocket and out through said aperture, a^1 . For a similar purpose in this form, the front wall, B, has a row of

apertures, b , opening from the pocket, E, along the upper forward corner of that pocket (referring to the same as at closed position of said front wall); and a second row of ventilating apertures, b^1 , is formed 70 through the said front wall immediately above the junction of the deflector, K, with said front wall.

In Figures 7, 8 and 9 there is shown another modification of the means for storing 75 the cable in the case, consisting of bracket posts, L and L¹, mounted on the opposite end walls of the case for receiving the cable coiled about them and intermediately around the handle of the iron, as may be understood 80 most clearly from Figure 9.

I claim:—

1. A container for the purpose indicated having a hinged closure member and means for carrying the electric cable of the iron in 85 a position out of contact with the latter, said means being mounted on the inner side of said closure member and positioned thereon for holding the cable in a position at one side of the handle of the iron when the closure member is in closed position.

2. A container for the purpose indicated, having a hinged top cover and means for carrying the electric cable of the iron out of 95 contact with the latter mounted on the inner side of said top cover, and positioned therein for carrying the cable at one side of the handle of the iron when said top cover is in closed position.

3. A container for the purpose indicated, having a hinged front and means for carrying the electric cable of the iron out of contact with the body of the iron, said means mounted on the inner side of said hinged front and positioned thereon for carrying the cable above the body of the iron and at 100 the forward side of the handle thereof when said hinged front is in closed position.

4. A container for the purpose indicated having the top and front wall hinged at 110 their rear and bottom edges respectively for opening respectively rearwardly upward and downwardly forward, and separate means for carrying the electric cable of the iron mounted respectively on the under side of the cover and inner side of the front wall, and positioned on said parts respectively for carrying the cable out of contact with the body of the iron at the closed position of said cover and front.

5. A container for the purpose indicated having a hinged top, and a pocket mounted on the under side of said top positioned thereon for carrying the electric cable of the iron above the body of the iron behind the handle thereof when the iron is in position in the container and the top is at closed position.

6. A container for the purpose indicated having a front wall hinged at the bottom for

opening down forwardly for removal and insertion of the iron and a pocket mounted on the inner side of said hinged front wall for carrying the electric cable of the iron above the body of the iron and forward of the handle thereof when the iron is in position in the container and the front wall is at closed position.

7. A container for the purpose indicated
10 having a closure member hinged for opening to insert and remove the iron and having a pocket mounted upon the inner side of the wall, adapted to contain the electric cable of the iron out of contact with any part of the
15 latter, said pocket being completely closed as to communication with the cavity of the container when the closure member is at closed position, the portion of the wall upon which the pocket is mounted having venti-
20 lating apertures positioned for causing circulation of air from the exterior of the casing through the pocket.

8. A container for the purpose indicated

having a hinged closure member for opening to insert and remove the iron and a pocket 25 mounted on the inner side of said closure member for carrying the electric cable of the iron and having an opening for inserting and removing the cable, said opening being formed in a side of the pocket which seats 30 against an inner wall of the case at closed position of the container, whereby at said closed position said opening is closed for cutting off communication between the cavity of the pocket and the remainder of the 35 cavity of the casing, said pocket and the wall of the case against which the pocket seats at closed position having co-operating ventilating apertures for causing circulation of air from the outside through the pocket 40 without circulation through the remainder of the cavity of the casing.

In testimony whereof, I have hereunto set my hand at Chicago, Illinois, this 23 day of February, 1924.

MICHAEL W. McARDLE.
